UNITED STATES PATENT OFFICE.

JOHN WAITCH, OF PITTSBURGH, PENNSYLVANIA, ASSIGNOR OF ONE-HALF TO FRANK LASEVICIUS, OF LAPORTE, INDIANA.

WINDOW-CLOSING LOCK.

Application filed May 3, 1920. Serial No. 378,378.

To all whom it may concern:

Be it known that I, JOHN WAITCH, a citizen of Lithuania, residing at Pittsburgh, county of Allegheny, and State of Pennsylvania, have invented certain new and useful Improvements in Window-Closing Locks, of which the following is a specification.

The present invention relates to improvements in window sash holders and locks, and it is the object to provide a device of this kind of great practicability and strength and adapted to be cheaply manufactured.

Another object of the invention is the provision of a device for allowing the locking of a raised window in any relative position of the sashes.

A further object of the invention is the provision of a window lock and sash holder of the above character which will possess advantages in points of efficiency and durability, and which is simple in construction and operation.

These objects are attained by the novel construction and combination of parts hereinafter described and shown in the accompanying drawing forming a material part of this disclosure, and in which—

Figure 1 is a front view showing the application of the device constructed according to the invention to a window, and

Figure 2 is a side view thereof partly in section.

Referring to the drawing in detail the numeral 10 designates the upper, and 11 the lower frame of a window. Secured to the front face of the upper window frame is a metal plate 12 by means of screws 13 or the like fastening means. This plate is pro-

vided at uniformly spaced intervals with T 40 slots 14.

A locking member 15 of the customary well known construction is secured with its base 16 by means of screws 17 or the like to the upper edge of lower window frame 11, 45 and its movable catch provided with the customary handle 19 and locking member 20 slides upon a support 21 in the well known manner to engage one or the other of the T slots 14 for locking the window sashes 50 in any relative position to each other.

While I have shown and described the preferred form of my invention it will be obvious that various changes in the details of construction may be resorted to for successfully carrying my invention into practice, without sacrificing any of the novel features or departing from the scope of the invention as defined by the appended claim.

Having thus described my invention, what I claim and desire to secure by Letters Patent of the United States is—

A device of the character described, comprising in combination with the upper and lower frame of a window, a plate provided with a plurality of T sockets, screws for securing said plate to the inner front face of the upper window frame, a member secured to the upper edge of the lower window frame, and a movable catch adapted to engage with its locking member, any one of said sockets for holding and locking the window frames in their relative adjusted positions.

In testimony whereof I have affixed my 75 signature.

JOHN WAITCH.
